DESIGN FOR A SHIP CLOCK

Abraham Levy and Joseph F. Punzak, Brooklyn, N. Y., assignors to United Metal Goods Manufacturing Co. Inc., Brooklyn, N. Y., a corporation of New York

Application May 20, 1940, Serial No. 92,480

Term of patent 3½ years

To all whom it may concern:

Be it known that we, Abraham Levy, a citizen of the United States, residing at Brooklyn, in the county of Kings and State of New York, and Joseph F. Punzak, a citizen of the United States, residing at Brooklyn, in the county of Kings and State of New York, have invented a new, original, and ornamental Design for a Ship Clock, of which the following is a specification, reference being had to the accompanying drawing, forming part thereof.

Figure 1 is a side elevational view of a ship clock showing our new design;

Figure 2 is an end view looking toward the bow end of the ship;

Figure 3 is an end view looking toward the stern end; and

Figure 4 is a plan view of the same.

The dominant features of our design reside in the specific configuration and arrangement of the parts shown in full lines, the broken lines shown in Fig. 1 being omitted from Figs. 2, 3 and 4 for convenience of illustration.

We claim:

The ornamental design for a ship clock, as shown and described.

ABRAHAM LEVY.
JOSEPH F. PUNZAK.
